UNITED STATES PATENT OFFICE.

GEORGE E. WILSON, OF STILLWATER, MINNESOTA.

STRAW-STACKER.

SPECIFICATION forming part of Letters Patent No. 536,054, dated March 19, 1895.

Application filed August 16, 1894. Serial No. 520,464. (No model.)

To all whom it may concern:

Be it known that I, GEORGE E. WILSON, a citizen of the United States, residing at Stillwater, in the county of Washington and State 5 of Minnesota, have invented certain new and useful Improvements in Straw-Stackers; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

15 This invention relates to improvements in the straw-stacking mechanisms which are constructed separately from the thrashers and are mounted on independent vehicle supports.

The invention has several objects. One is 20 to so arrange and form the parts that the machine can be made less heavy and complicated than are those which have been heretofore used. Another is to provide a peculiarly constructed lock for the clutch which regulates 25 the movements of the parts that cause the horizontal vibrating of the carrier; and there are other objects aimed at which will be fully understood from the description below, in connection with the drawings.

30 Figure 1 is a side elevation of the stacking mechanism embodying my improvements, the carrier being shown as elevated. Fig. 2 is a side view showing the carrier lowered. Fig. 3 is a view from the inside of one of the elevating sheaves and the parts adjacent to it. Fig. 4 is a section on the line $x-x$, Fig. 3. Figs. 4^a, and 4^b, show modifications as to the 35 rope groove. Fig. 5 shows a means of fastening for the track bar. Fig. 6 is a plan view 40 of the oscillating platform and of a portion of the vehicle frame. Fig. 7 is a section on the line $y-y$. Fig. 8 is a top view of some of the parts looking downward from a plane above that from which Fig. 6 is taken. Figs. 45 9 to 18 show in detail the parts for moving and locking the clutch. Fig. 19 is a face view of the same when assembled. Fig. 20 is a plan view of the same in connection with the clutch and the clutch lever. Figs. 21 to 27 50 inclusive show successive positions of the several parts of the clutch and its shifting and locking mechanism.

In the drawings, A, represents a platform or main frame as a whole. It is mounted upon a vehicle indicated by B, supported upon 55 wheels, and which can be of any suitable form so that the machine can be transported readily from place to place with the thrasher.

The platform or main frame A, is shown as comprising the sills A', and the cross girts A². 60 From these parts there depend hanger brackets d, which are cast integral with or secured to a toothed ring D. This ring constitutes an enlarged journal around the axis of which the platform can vibrate or oscillate, it being 65 held in bearings formed of curved and flanged bars C, C, which are bolted to the vehicle frame B, this frame having side sills B', B', and cross girts B², B³, B⁴, B⁵. In many of the mechanisms of this sort as heretofore constructed, use has been made of anti-friction 70 wheels or rollers, but owing to the unsteadiness resulting therefrom much trouble has been experienced with them, and I have devised the form of mounting herein shown, namely, the 75 ring D, with a horizontal flange d', in conjunction with the flange and curved brackets C, to obviate much trouble.

The ring and platform have imparted to them reciprocating rotary movements by the 80 following devices.

E, represents a shaft mounted transversely in the vehicle frame B, it having a belt pulley E', for receiving power. It carries a worm 85 e, for actuating the devices which vibrate the carrier, and also carries a beveled wheel G, for driving the carrier belt, said wheel meshing with the pinion G' on the lower end of shaft G². The latter is mounted in the bracket stand g', and carries at its upper end a 90 sprocket wheel g. The worm e, engages with a worm-wheel F, on shaft f, which is mounted on the vehicle frame longitudinally of the machine. It supports two loose beveled pinions H, and H', each meshing with a beveled 95 wheel I. This wheel is secured to a vertical shaft I', mounted in the bracket bar i. At its upper end there is a pinion J, which meshes with the teeth of the cogged ring D; and it will be seen that the ring and the platform 100 will be turned in one direction or the other according as the beveled pinions H, and H', are in engagement with the power devices. These pinions have square clutch faces, h,

and with them alternately the double clutch member K, feathered on shaft k, is adapted to engage. The clutch teeth have square faces as at h', h', for a purpose to be described. 5 The clutch member is shifted by the lever K', which is pivoted at k, to a supporting bar k². Preferably this lever is of a bell crank shape, and as it vibrates it throws the clutch member K, from one beveled wheel to the other.

It is desirable to prevent any accidental displacement of the clutch when the machine is in operation, and to accomplish this I combine with the parts above described a positively acting lock adapted to resist for a certain period of time any inward movement of the clutch member K, whether caused by the back pressure from the beveled wheel upon the clutch or by jolts, vibrations or sudden movements of the machine.

The shipping lever K', has its outer end k', passed through a lock lever L. The latter is pivoted at l, to a plate N, which is secured to the cross girt B⁴, of the vehicle frame, said plate preferably having an outwardly projecting lug, see Figs. 14 and 15, to serve as a pilot. Lever L is locked in one or the other of two positions by means of dogs or latches M, M', each of which is pivoted at m, to the aforesaid plate N. The dogs have teeth m', m², respectively adapted to engage with the teeth l', l², on the upper end of the lever L, and are also formed with cam-like edges m³.

O indicates a tripping plate or bar, the lower end of which is also pivotally connected to the outer end k', of the shipping lever. It has a curvilinear slot o, through which projects the stud l, that serves as aforesaid as the pivot for the lever L, whereby the plate or bar O, is allowed limited movement independent of the lever, and yet can be moved therewith because of both being supported on the end k', of lever K'. This bar or plate O, is further provided with inwardly projecting lugs o', o², which are so situated that they can at proper times impinge upon the cam-like edges at m³, of the latches or dogs M, M', and also can impinge upon the upper end of the lever L.

50 O³, is a finger or arm projecting inward from the upper end of the trip-plate O.

P, is a swinging weight which is supported from a pivot at p, at the upper end of the swinging plate O.

55 Q, indicates the support for the other part of the trip, it being preferably formed of a segment bar secured to the oscillating platform concentric with the central vertical shaft G², and carrying adjustable trip pins q, 60 adapted to be inserted into one or another of a series of apertures at q'. Varying the position of these pins varies the arc through which the stacking mechanism is vibrated horizontally. The above described projection or arm O³, on the trip plate O, lies in the path of these trip pins q.

The operation of the above described parts

will be readily understood. When the machine is in operation and the shaft e, is rotating, the pinion J, will be revolved by the worm e, worm wheel F, shaft f, clutch K, and wheel H, or H'; and said pinion J, will in turn rotate the ring D, and platform A. Now, if the parts are in the position shown in Figs. 21 and 22, wheel H', will be engaged with clutch K, and shaft f, and the parts will be rotated in such direction that the ring will be turned in the direction of the arrow 1, in Figs. 21 and 6. The ring will continue moving in this direction until the trip pin q, strikes the arm O³. (See Fig. 21.) After these parts contact, the trip plate O, is caused to swing on its pivot from the position shown in Fig. 21, to that shown in Fig. 23, and then to those in Figs. 25 and 26. During the swinging the lug o², impinges upon cam edge m³, of latch or dog M, and as a result the teeth m² are lifted out of engagement with teeth l². This frees the lever L, from the positive lock, but it will not be moved quite yet although the plate O, still swings to the left under pressure of pin q, and as soon as it has moved beyond the line of the center of gravity the weight P, begins to carry it down. As soon as the weight has reached the upper end of lever L, and the end of the slot o, has reached the stud l, the lever L, will be rocked upon said stud l, and the lower end of the lever L, and plate O, will be moved to the right, which latter movement disengages clutch member K, from wheel H'; and the weight of the part P, now draws the clutch toward the wheel H; but an instantaneous engagement of the clutch and wheel is not effected because of the square ends or faces of the teeth at h, h'— that is to say, the vibrating or oscillating of the straw carrier is temporarily stopped at each end of its throw, the result being that the stack is piled up square or flat on top and slanting or inclined ends are avoided; but as the weight P, is still exerting its pressure on the lever L, and plate O, the clutch K, will engage with wheel H, as soon as the partial rotation of the clutch has brought its teeth into line with the recesses in the wheel, as will be readily understood by comparing Figs. 22, 24 and 27. When the lever L, is in the central or vertical position shown in Fig. 25, the clutch member K, will be in the neutral position shown in Fig. 24. When the parts at L, O, and P, are in the position shown in Fig. 26, the clutch member will be situated as indicated in Fig. 27, and at this time the dog M', will be in positive engagement with the lever L, and the clutch member will be held rigidly to wheel H, and will be so held until the second pin q², comes into contact with the arm O³, of plate O.

The instant that the clutch member engages with the wheel H the pinion J, will be reversed, and the ring B, will revolve in the opposite direction, and continue so revolving until the plate O, and the lever L, have been thrown into the positions shown in Fig. 21.

The trip mechanism comprises as its essential parts the plate or bar O and the pin or pins q, the other above described devices combined with these acting to govern or regulate the tripping action with respect to the clutch.

It will be seen that I obviate entirely the use of springs, that I provide a positive lock, that I insure a temporary stoppage of the stacker at the ends of its horizontal movements, and that I carry the clutch firmly and promptly from one of the reversing wheels to the other.

The sprocket wheel g, is connected with the sprocket wheel G³, on a vertical shaft g², which carries the beveled wheel g⁴, meshing with wheel g⁵. This wheel g⁵, is on a shaft R, which is supported from the platform and carries a sprocket wheel R', connected to the driving shaft R², of the straw carrier by chain r. The carrier frame is indicated by S, and is made in two sections s, s', hinged together at s'. The endless carrier itself may be made in any suitable way, and is mounted on sprocket shafts at the ends. It is desirable to have the carrier frame as light as possible without decreasing its strength, and I have simplified the construction and have made the frame lighter but without decreasing its strength because of the use of the truss rod T, connected to and supported upon the truss brackets at t, t', t''.

U, U, indicate uprights which are rigidly secured to the platform or main frame at one end, and V, V, are links or hinged uprights pivoted to the front end and also pivoted to the forward end of the carrier frame.

As is well known, it is desirable to impart to the carrier frame not only a vertical swinging motion of its front end but also a forward motion as it swings upward so that its upper end shall always be in the same vertical lines. To accomplish this, various mechanisms have been devised or suggested. In some, use has been made of four or more pivoted links connected to the rear, together with a cam track on the under side of the carrier frame and rollers and a rising and falling roller shaft adapted to be drawn up and down by a rope. In others use has been made of peculiarly curved bars fastened to the platform, and with traveling wheels or rollers secured to the carrier frame and arranged to be moved up and down on said track. In still another class of these machines, use has been made of curved brackets or track bars secured to the carrier frame, and rising and falling rollers and cross shafts, together with screw-threaded rods engaging with nuts connected with the wheels and cross shaft. I have simplified all of this part of the machine, and while retaining the requisite strength, have provided for the several movements by using fewer and lighter elements of construction. I employ only two wheels or rollers which serve both as sheaves for the ropes and also as anti-friction supports for the carrier frame, they being shown at W, W, and being secured stationarily to the upper ends

of the uprights U. Over these pass the two ropes X, X, which are each connected at one end to the carrier frame and at the other end to the winding mechanism on the platform. The latter may be of any preferred sort. As shown it consists of a shaft X', mounted on the front uprights U, and provided with drums or rope wheels x, and the worm wheel x', with which engages the worm x², rotated by crank x³. The ropes after passing over the pulleys W, W, are secured to the track bars Y, and are fastened to the carrier frame.

The bars are peculiar in shape and arrangement. At their front or upper ends each has a part y, approximating straight lines, and at the lower end a convex or curved part as at y'. A portion of these track bars is extended above the carrier frame so that the latter can be lowered readily (see Fig. 2) and yet maintain its bearing upon or against the anti-friction rollers. Owing to the peculiar shape and arrangement of these track bars Y, the outer end of the carrier will be first swung up around the shaft R², as a practically stationary pivot, this continuing so long as the straight parts y, of the bars Y, are in contact with the roller W; but as soon as the convex or curved parts y', reach the rollers, the above described compound movement of the carrier frame is caused, that is to say, its outer end continues to rise, but at the same time it is thrown forward. The rope is secured at y², to the track bars; and in order to prevent the bars of the wheel W, from slipping or moving laterally relatively to each other, I form grooves in the one or the other or both, as shown at y³, y⁴, Figs. 3 and 4, and the ropes can seat themselves in said grooves, acting as locks to prevent any lateral slipping, and at the same time permitting the bars to ride freely on the wheels or rollers. Some of the purposes of the construction, however, can be attained if the track bar Y, the anti-friction wheel W, and the rope X, are modified in their construction with respect to the groove, as is shown in Figs. 4^a, and 4^b.

I am aware of the fact that use has heretofore been made of a curvilinear track bar secured to the bed or platform in conjunction with an annular brace frame projecting downward from the carrier frame, with shifting wheel or rollers mounted upon the carrier frame, and adapted to be drawn up and down upon the curvilinear bars; but there are a number of objections incident to this construction, which are obviated when use is made of one like that which I have devised. In order to get the desired positions of the carrier frame at the different elevations it is necessary with the earlier constructions to have a dropping or depending frame or support to carry the anti-friction wheels, and in other respects the mechanism is made more complicated than that herein, which upon examination of the drawings will be seen to be reduced to the utmost simplicity. The wheels being stationary and

the rope being connected to the curved bars insures a firmness of connection for the latter and an accuracy in the support for the carrier.

5. In Figs. 1, 2 and 8, it will be seen that the frame bars or supports A' , A^2 , of the oscillating platform are so secured to the toothed ring that the vertical center of the frame shall be behind the axis of said ring, this construction being preferably in the larger and longer stackers rather than that shown in Figs. 6 and 7, the frame A' , A^2 , in the latter being concentric with the ring D .

When the upper frame is thrown backward in relation to the axis, there is less liability for the machine to tip or turn over when the carrier is in operation and is swung away from the central longitudinal line of the vehicle.

What I claim is—

20. 1. In a straw stacker, the combination with a horizontal vibratable platform, of the longitudinally movable and vertically vibratable carrier frame supported at the rear upon vibratable links, the curved guiding bars, and the fixed rollers which support the front part of the carrier frame, substantially as set forth.

2. In a straw stacker, the combination with the carrier frame and the links at the rear thereof, one upon each side, of the bars Y rigidly secured to and rising and falling with the carrier frame, which have the rear convex portion and the forward straight portion, and the stationary rollers for supporting said track bars, substantially as set forth.

35. 3. In a straw stacker, the combination of the vibrating platform, the front uprights rigidly secured thereto, the rear vibratable links, the carrier frame pivoted to said links, supporting rollers secured stationarily to the front rigid uprights, and the bars Y secured to the carrier frame and the rear part depending below it, said bars being shaped substantially as set forth whereby as the carrier frame rises, the outer end swings upward and then 45 swings both forward and upward, as described.

4. In a straw stacker, the combination with the vibratable platform, and the vertically moving carrier frame, of the bars Y , the ropes having their ends fixed in relation to the carrier frame, and the fixed rollers connected to the platform, substantially as set forth.

5. In a straw stacker, the combination of the horizontally vibrating platform, the rollers secured to said platform, the vertically vibrating carrier frame resting directly upon said rollers, the ropes passing over said rollers and having their ends fixed in relation to the carrier frame, substantially as described.

6. In a straw stacker, the combination of the 60 vibrating platform, the supporting rollers secured stationarily thereto, the vertically vibrating carrier frame resting directly upon said rollers, the ropes passing over the said rollers and means for engaging laterally with 65 the ropes to prevent the carrier frame from moving laterally in relation to the rollers, substantially as set forth.

7. The combination with the horizontal vibrating platform A having links V pivoted thereto, the rigid uprights U , the carrier frame pivotally connected to links V , the bars Y secured to the carrier frame, rollers W interposed between the bars and the uprights U , the ropes passing over said rollers W and seated in grooves in the bars Y , substantially as set forth.

8. In a straw stacker the combination of the vibrating platform A , the links V , the uprights U , the rollers W secured to said uprights, the carrier frame S , the curved bars Y secured to the carrier frame and resting directly upon said rollers, and means for moving said carrier frame bodily forward and back, relatively to the rollers, substantially as described.

9. In a straw stacker, the combination with the platform, the means for oscillating it, and the reversing mechanism, of a lever connected with the reversing mechanism, a positively acting lock for said lever, the trip plate actuated by the platform for opening the lock, and the weight for moving the reversing mechanism, substantially as set forth.

10. In a straw stacker, the combination of the carrier frame, the vibrating platform which supports it, means for turning said platform alternately in opposite directions around its axis, a reversing mechanism, and a lock for said reversing mechanism having a lever L , the dogs, the trip plate and the weight, substantially as set forth.

11. In a straw stacker, the combination of the carrier frame, the vibrating platform which supports it, mechanism for moving said platform around its axis in opposite directions alternately, the reversing mechanism, a lever engaging with said reversing mechanism, a positively acting dog or catch for said lever, and the trip plate adapted to move a limited distance independently of said lever and also to move simultaneously therewith for throwing the reversing mechanism, substantially as set forth.

12. In a straw stacker, the combination of the carrier frame, the horizontally vibrating platform which supports it, means for alternately moving the platform axially in opposite directions, the reversing mechanism, the lock lever L engaging with said reversing mechanism, the positively acting catch for said lever, the trip bar or plate O adapted to release the lock and to move the lever L , and the weight engaging with said plate O , substantially as set forth.

13. The combination with the reversing mechanism of a straw stacker, of the lever L , the tooth dogs $M M'$ engaging with the lever, the plate O having the slot o whereby it is adapted independently of the lever L , and carrying means engaging with the dogs $M M'$ and with lever L , substantially as set forth.

14. The combination with the reversing mechanism of a straw stacker, of the lock lever L , pivoted at l and pivotally connected to

the reversing mechanism, the dogs or catches M M' engaging with the lock lever, the trip plate O pivoted to the reversing mechanism and having the slot o, means carried by said 5 plate O for opening the lock and for engaging with the lever L, and the weight P, substantially as set forth.

In testimony whereof I affix my signature in presence of two witnesses.

GEORGE E. WILSON.
